DESIGN FOR A SACHET BASKET

Thomas F. Bagshaw, San Francisco, Calif.

Application December 5, 1939, Serial No. 88,707

Term of patent 7 years

To all whom it may concern:

Be it known that I, Thomas F. Bagshaw, a citizen of the United States of America, residing at San Francisco, in the county of San Francisco and State of California, have invented a new, original, and ornamental Design for a Sachet Basket, of which the following is a specification, reference being had to the accompanying drawing, forming a part thereof.

I claim:

The ornamental design for a sachet basket substantially as shown and described.

THOMAS F. BAGSHAW.
